WINDOW VENTILATION APPARATUS

Allen McLaughlin, Ferndale, Mich.

Application February 5, 1932, Serial No. 591,039

10 Claims. (Cl. 98—94)

This invention relates to room ventilating apparatus and it has particular relation to ventilating apparatus applicable for mechanically circulating air through windows of rooms.

5 An object of the invention is to provide an inexpensive and convenient ventilating apparatus which is attachable directly to the sash of a kitchen or any other window where ventilating apparatus is desirable and which is operable when 10 the window is in a closed position; to provide ventilating apparatus adapted to be secured in operative position in a closed window which does not appreciably diminish the amount of light normally received through the window from the outside and which can be employed without curtain 15 guards, screens and other accessories now generally required for the operation of window ventilating apparatus; and in general, to provide a neat appearing, compact and efficient window 20 ventilating apparatus which can be operated at any time merely by pulling a cord or by actuating some similar mechanism controlling device.

In the drawings:

25 Fig. 1 illustrates an ordinary glass or other transparent window in which ventilating apparatus constructed according to the principles of this invention is embraced.

Fig. 2 is a fragmentary view of the window ventilating apparatus illustrated by Fig. 1 as it would appear installed in the window casing of a house. The figure is taken substantially on line 2—2 of Fig. 1.

30 Fig. 3 is a fragmentary cross-sectional view of the structure illustrated by Fig. 1 except that it shows the structure as it might appear on line 3—3 thereof.

35 Fig. 4 is a cross-sectional view taken substantially on line 4—4 of Fig. 3 and illustrating particularly a motor switch controlling mechanism embraced in the apparatus.

40 Fig. 5 is a fragmentary front elevational view of a window having ventilating apparatus constructed according to this invention secured thereto; that is, the view illustrates the window structure as it might appear from the outside of a building.

45 Fig. 6 is a fragmentary cross-sectional view of the structure illustrated by Fig. 1 as it might appear on line 6—6 thereof.

Fig. 7 is a cross-sectional view of a window ventilation apparatus illustrating another form of ventilation controlling apparatus embracing the principles of this invention.

50 Fig. 8 is a view of the apparatus illustrated by

Fig. 7, taken substantially on line 8—8 thereon.

Fig. 9 is a cross-sectional view of the structure disclosed by Fig. 7 except that in Fig. 9 the parts of the mechanism are shown as they might appear looking in the direction of the arrows from line 9—9 on Fig. 8.

Fig. 10 is a cross-sectional view of the structure substantially as shown in Fig. 7 except that the parts are shown on a smaller scale and in 10 a different operative position.

Fig. 11 is a view also upon a reduced scale of the structure as illustrated by Fig. 9 except that in Fig. 11 the parts are arranged in a different 15 operative position.

Referring particularly to Fig. 1, a window 10, employed in practicing the invention, comprises a rectangular frame or sash 11 having a pane of glass or other transparent plate 12 inserted therein. The sash is adaptable for mounting in a window casing either to rotate upon hinges about the edge thereof or (see Fig. 2) to slide within 20 grooves 13 formed by strips 14 secured in spaced relation around the inside of a casing 16.

The pane of glass 12 is provided with an aperture of suitable formation in an upper portion thereof, in which a frame 17 of an air circulating or ventilating apparatus 18 is mounted. The upper part of the frame 17 has an inner edge portion 19 which abuts the lower front edge of the 25 upper section of the window sash 11 and has also an upwardly extending flange 21 abutting the front surface of the window sash. The flange 21 is secured to sash 11 by screws 22 and hence the weight of the frame 17 and other appurtenances 30 thereon is almost entirely supported by and is suspended beneath the upper section of the sash. The frame 17 also has a recess formed in the outer surface thereof which receives resilient gaskets 35 23 against which the edges of the glass 12 around 40 the aperture therein are secured by a removable strip 24 and screws 26.

As best illustrated in Figs. 3 and 5 the upper edge of the frame 17 has formed integrally therewith a horizontally disposed and outwardly projecting ledge 27, the opposite extremities of which are flanged downwardly as is indicated at 28 for supporting inwardly projecting and aligned pins 29. The inner extremities of such pins are pivotally received in openings formed at the opposite 45 extremities of an upper horizontal portion 31 of a supplemental frame 32 having a groove or recess around the inner surface thereof in which the edges of a correspondingly shaped plate of glass 33 are received. As best illustrated in Fig. 6 the 50 55

glass is mounted between suitable resilient gaskets 34 and is secured within the groove in the frame 32 by a removable strip or molding 36 attached by screws 37.

- 5 The frame 32 is substantially of the same size as the frame 17 and the two are provided with interfitting and overlapping edges as indicated at 38 in Fig. 6 which tend to prevent moisture from obtaining access to the inside of the frame 17.
- 10 The upper horizontal portion 31 of the frame 32 is provided with properly curved edges indicated at 39 in Fig. 3 which permit the frame to be rotated outwardly on the pins 29 without interference by the ledge 27 or other adjacent parts of the structure.

15 In order to provide means for suspending a motor 41 in a substantially central position within the frame 17, the latter is provided with diametrically opposed lugs 42 and 43 (see Fig. 2) to which the opposite extremities of a motor supporting yoke 44 are attached by screws 46. For the purpose of illustration, the yoke 44 is constructed of two substantially identical sections 45 each having an overlapping semicircular portion 47, the opposite ends of which portions are secured together around the motor 41 by bolts 48. The motor 41 is so positioned within the yoke 44 that a fan 51 secured to a drive shaft 52 thereof is free to rotate in front of the yoke and in a region directly inside of the interfitting edges 38 of the frames 17 and 32.

20 The electrical current for the motor 41 is supplied by a pair of conductors 53 extending through an opening 54 formed longitudinally of one section 35 of the yoke 44 and in one of which conductors a conventional snap action or toggle switch 56 is inserted. The switch 56, which is contained in a box or casing 57 provided at an upper corner of the frame 17, has an actuating lever 58, the end 25 of which is movably confined within an opening 59 formed in an intermediate portion of a lever 61. One end 62 of the lever 61 projects outwardly through a slot 63 formed in the rear of the casing 57 and there has a suitable operating cord 75 attached thereto while the opposite end thereof 30 projects downwardly in parallel relation to a slot 64 formed in a removable plate 66 secured to the casing 57 by screws 67 and by which access may be had to the interior of the casing. Such front plate is provided with an inwardly projecting lug 68 having a screw 69 axially slidably disposed in 35 a transverse opening therein. The lever 61 is secured rigidly on the end of the screw 69 at a point slightly spaced laterally from the opening 59. Between the lever 61 and the lug 68 is a small coil 40 spring 71 which tends to urge the lever away from the lug and against a side of the opening 63 in the casing 57. This side of the opening 63 is provided with a laterally disposed recess 72.

45 The position of the recess 72 with respect to the opening 63 is such that when the end 62 of the lever 61 is pulled downwardly the spring 71 will push the lever 61 into the slot when the lever reaches its downward limit of movement. Such movement of the lever 61 also carries with it the lever 58 by which the switch 56 is actuated, to provide an electrical circuit through the motor 41 when the lever assumes its lowest position.

50 As best shown in Fig. 3, the opposite or downwardly projecting end of the lever 62 is pivotally connected, as indicated at 76, to one end of a link 77, the opposite end of which is in turn connected by a pin 78 to an inside portion of the auxiliary window frame 32.

55 When the end 61 of the lever 62 is pressed

downwardly to close the electrical circuit through the motor 41, the opposite end of the lever and the link 77 move outwardly through the notch 64 and, in assuming a resultant and an approximately aligned relation, tend to elevate the frame 32 and the window 33 into the position indicated in dot and dash lines in Fig. 2.

60 When the window is thus opened and the motor 41 is energized as a result thereof, the fan 51 discharges a continuing blast of air outwardly through the frame 17 from a room in which ventilation is desired. Such blast of air keeps insects, dirt, etc. from entering a room through the frame 17 without the necessity for the employment of screens and inasmuch as there are no 15 obstructions in front of the fan 51 when the window 33 is elevated, it carries grease and moisture in suspension in the air in the room entirely from the building without engaging anything on which such particles might collect. It will also 20 be observed that the fan 51 is located so far outside of the window glass 12 and is so protected by the motor and the motor bracket 44 that guards or cages normally employed for keeping window curtains and blinds out of contact with 25 the fan are not required.

30 In operating the ventilating apparatus disclosed herein, it is necessary only to pull downwardly upon the cord 75 until the end 62 of the lever 61 slides into the notch 72. In such position the 30 motor 41 will be energized and the frame 32 will be elevated into such position as to permit the air from the fan 51 to be discharged from the room in which the window casing 11 is employed. In view of the character of the switch 56, it will 35 be apparent that it will not be moved to closed circuit position until the lever 61, and consequently the auxiliary window, has moved to substantially full open position.

40 When no further ventilation is required, the cord 75 is simply pulled in such way as to release the lever 62 from the notch 72 as a result of which the weight of the frame 32 will close the auxiliary window upon the frame 17 and the switch 56 will automatically be actuated to de-energize the 45 motor 41. In such position it will be apparent that the window is tightly closed against outside weather and can be employed for the purpose of illuminating the interior of a room practically the same as though the window did not embrace 50 such ventilating apparatus.

45 In the structure disclosed by Figs. 7 to 11 inclusive, the window ventilating apparatus is provided with a slightly different form of device for controlling the operation thereof. In such structure, to which corresponding reference numerals heretofore applied are employed, a pair of springs 81 are provided with coil portions intermediate their ends which surround the extended threaded ends of the pins 29 and are retained thereon by 60 nuts 82. One end of each of the springs 81 bears against the frame 17 adjacent the opposite ends of the flange 21 projecting upwardly therefrom, while the opposite ends thereof bear against the inner side of the auxiliary frame 32 in regions 65 between the upper and lower extremity thereof. The springs 81 are so constructed that when installed in this manner they tend to retain the auxiliary frame in its open position.

70 In the structure disclosed by these figures the casing 57 is of somewhat different shape from that employed in the structure disclosed by Figs. 1 to 6 and has projecting from a wall thereof adjacent the frame 32 a lug 83 on the outer end of which a small grooved ratchet wheel 84 is ro- 75

tatably mounted upon a ratchet shaft 86. A flexible chain 87 secured to the wheel 84 by a pin 88 extends within the groove in the wheel 84 around the side thereof adjacent the frame 32 and 5 thence in the opposite direction around a portion of the grooved outer surface of a roller 89 which is pivotally mounted on a pin 91 projecting from the side of the casing 57. The chain then projects outwardly of the casing 57 through an 10 aperture 92 formed in a lower portion thereof and is there available for the operation of the apparatus as will be hereinafter described.

One end of the ratchet shaft 86 is provided with a relatively non-rotatable radially extending 15 disc 93 in which is formed a pair of notches 94 and 96. A pawl 97, adapted to extend alternatively within one of these notches, is pivotally mounted upon the ratchet wheel by a screw 98 and is held resiliently in such operative position 20 by a spring 99 engaging the pawl at one end and secured to the ratchet wheel at the other. Disposed around the ratchet shaft 86, upon the opposite side of the ratchet wheel 84 and between the latter and the boss 83, is a coil spring 101 25 having one of its ends attached to the ratchet wheel and the other to the boss. When the chain 87 is pulled downwardly, resulting in the rotation of the ratchet wheel 84, the coil spring 101 is compressed to a greater degree than before 30 and returns the ratchet wheel to its original position when the pull on the chain 87 is released.

Secured rigidly upon the opposite end of the ratchet shaft 86 beyond the boss 83 is an arm 102 having a pin 103 at the outer extremity thereof 35 on which is mounted a roller 104. A link 106 provided with a longitudinal opening or slot 108 therein, for receiving the roller 104, is pivoted by a bolt 109 to a lug 111 projecting outwardly from the wall of the casing 57 in a region somewhat 40 above and to one side of the boss 83. Secured by a pin 112 to the outer end of the link 106 is an arm 113, the opposite end of which projects outwardly through an opening in the casing indicated at 115 and is secured by a screw 114 to one 45 side of the auxiliary frame 32.

The arm 102 is so angularly disposed upon the ratchet shaft 86 that a line through the axis of the ratchet shaft and the roller 104 will be substantially perpendicular to the elongated slot 108 50 when the auxiliary frame 32 is closed.

When the chain 87 is pulled to open the window the pawl 97 engaging the slot 94 will rotate the arm 102 in the direction indicated by Fig. 11 and such rotation of the arm will swing the link 106 55 upon the pin 109 until the pin 88 supporting the chain 87 engages a pin 116 projecting outwardly from the casing 57. In such position the link 106 will have been depressed until a line between the axis of the shaft 86 and the axis of the roller 104 60 will again be normal to the slot 108, although it will extend in an opposite direction relative to the slot. In such position of the parts the frame 32 will be elevated into its open position and will there remain even when the chain 87 65 is released by reason of the dead center position of the arm 102 relative to the link 106.

As soon as the chain 87 is released the spring 101 will rotate the ratchet wheel 84 in a direction 70 opposite to that in which it was rotated by the chain and until the pawl 97 is engaged in the notch 96.

As soon as the pawl has assumed such position the auxiliary window may be closed against the 75 compression of the springs 81 merely by again

pulling upon the chain 87 and continuing the rotation of the arm 102 in the same direction as before and until it assumes the position illustrated by Fig. 9. In such position the auxiliary window cannot be opened from the outside because to do so would require the rotation of the link 106 upon the pin 109 directly against the normally disposed arm 102 and, therefore, the window is locked until such time as the chain 87 is again pulled from inside the window.

In having the auxiliary window close against the compression of the springs 81, the possibility of the breakage of glass is practically eliminated in view of the fact that with such springs the auxiliary window cannot be closed rapidly enough to cause a particularly violent engagement between the frames 17 and 32.

It is to be understood that a switch, such as that illustrated at 56, can be employed for controlling the operation of the motor in combination with the structure as disclosed by Figs. 7 to 11, merely by attaching such switch to the link 106 in the same manner in which it is attached and operated in the structure illustrated in the preceding figures.

In the distribution to the public of the window structure disclosed herein, it is apparent that the ventilating apparatus can be sold either with or without the window 10. It may be sold directly to a householder, for example, in which event it is necessary only to cut an aperture of proper shape in the pane of a window already installed and then to secure the apparatus in such opening as hereinbefore described.

It may be desirable in some instances to sell the window ventilating apparatus already installed in a pane of glass but not in a window frame. Under such circumstances the householder simply replaces an already installed pane of glass with one containing the ventilating apparatus.

While the window structure as herein disclosed constitutes a preferred form and application of the invention, it is to be understood that other structures differing widely from that herein disclosed are within the scope of the invention as defined by the appended claims.

I claim:

1. In combination, a window pane having an opening therein, a frame for said opening projecting outwardly beyond the plane of said pane, a closure for said opening at the outer extremity of said frame and movably associated therewith, a motor supported by said frame, a fan supported by 50 said motor outwardly beyond the plane of said pane and with its outer edges approximately in the plane of the outer edges of said frame, whereby the centrifugal effect of the fan on the air enhances the efficiency of the fan, and means for 55 operating said closure.

2. Ventilating apparatus including a window sash provided with a pane of glass, said pane having an opening therein, a bar attached to said sash adjacent said opening, a frame for said opening supported from said bar, and a closure for 60 said opening movably supported from said bar.

3. In combination with a ventilator having a movable closure, a support, a shaft rotatable in said support, a ratchet wheel fixed to said shaft, 70 a crank fixed to said shaft, a pivoted arm having a slot therein slidably receiving the end of said crank, a link pivotally secured at opposite ends to said closure and to the free end of said arm, and means freely movable with respect to said 75

- shaft engageable with said ratchet wheel to cause rotation of said shaft.
4. A ventilator structure including a frame having a closure member, means operable by alternate successive movements in the same linear direction for alternately fully opening and fully closing said closure member, and spring means opposing closing movement of said member.
5. A room ventilating structure comprising, in combination, a window sash, a pane of glass supported by said sash, said pane having an opening therein extending to an edge thereof, a frame fixed relative to said pane and embracing the margins of said pane at said opening, means for principally supporting said frame from said sash, a closure for said opening pivotally mounted on said frame, an electric motor supported by said frame, a fan disposed within said frame and driveable by said motor, and a common means for controlling the position of said closure and the operation of said motor.
6. A window structure comprising a sash and a transparent panel therein, said panel having an opening therein the edges of which extend to said sash, a frame for said opening embracing said panel about the margins of said opening, a motor supported by said frame, a fan supported by said motor for driving movement therefrom, and means directly connecting said frame and said sash whereby to support the weight of said frame, motor and fan independently of said panel and materially relieving said panel of the vibratory effects of said motor and fan in operation.
7. A window structure comprising a sash and a transparent panel therein, said panel having an opening therein the edges of which extend to said sash, a frame for said opening having a marginal channel for reception of said panel about the margins of said opening, vibration insulating means interposed between said panel and the walls of said channel sealing the space between said panel and said channel, a motor supported by said frame, a fan supported by said motor for driving movement therefrom, and means directly connecting said frame and said
- sash whereby to support the weight of said frame, motor and fan independently of said panel and materially relieving said panel of the vibratory effects of said motor and fan in operation.
8. In a ventilating mechanism, in combination, a frame having an opening therein, a closure for said opening pivotally supported on said frame, a crank, means for operating said crank in one direction of rotation only, a pivoted link having a slot therein, said crank being engaged in said slot whereby to oscillate said link upon rotation of said crank, and a second link connecting the first mentioned link to said closure, said crank and links being so constructed and arranged that said closure is moved from fully closed to fully opened position upon rotation of said crank through less than 180 degrees of angular movement and is moved from fully open to fully closed position only upon rotation of said crank through more than 180 degrees of angular movement.
9. A room ventilating structure comprising, in combination, a window sash, a pane of glass supported by said sash, said pane having an opening therein extending to an edge thereof, a frame fixed relative to said pane and enclosing the margins of said pane around said opening, means for securing said frame directly to said sash for support therefrom, a closure for said opening including a frame movably mounted on the first mentioned frame and a similarly shaped sheet of glass movable therewith embraced marginally by said closure frame, and means for operating of said closure.
10. In a ventilating structure, in combination, a window sash, a pane of glass supported thereby, said pane having a portion cut away from a horizontally extending edge thereof at a location spaced from the vertically extending edges thereof to form an opening therein, a frame for said opening supported directly from the adjacent portion of said sash, and a motor driven fan supported by said frame in co-operative relation with respect to said opening.

ALLEN McLAUGHLIN.
